ASH RECEPTACLE

Filed July 1, 1939

UNITED STATES PATENT OFFICE

2,245,882

ASH RECEPTACLE

John Visser, Grand Rapids, Mich., assignor, by
mesne assignments, to Reconstruction Finance
Corporation, Detroit, Mich., a corporation of
the United States

Application July 1, 1939, Serial No. 282,432

2 Claims. (Cl. 206—19.5)

This invention relates to a container adapted to be moved in and out below a supporting structure, and more particularly to an ash receptacle operable in a drawer-like manner below the lower edge of a supporting panel.

An object of this invention is to provide an improved supporting structure for a container in which structure the container is adapted to be moved into and out of accessible position with a minimum amount of binding and friction.

Another object of this invention is to provide an ash receptacle and a supporting structure therefor with improved resilient means to exert a pressure between the receptacle and the supporting structure to hold the receptacle against rattling in the supporting structure irrespective of whether the receptacle be in an open or closed position.

Still another object of this invention is to provide a snuffer and an anti-rattle spring combined and made of a single piece of metal and easy and economical to manufacture and assemble.

Another object of this invention is to provide an improved anti-rattle spring for a slidable ash receptacle, which is adapted to bear against the ash receptacle support at two longitudinally spaced points in order to prevent rocking or tilting of the ash receptacle at all times.

Another object of this invention is to provide a snuffer formed as a part of an anti-rattle spring of an ash receptacle, whereby the addition of the snuffer to the structure requires little or no added material or labor.

A still further object of the present invention is to provide a simple and effective means of securing an anti-rattle spring to a slidable ash receptacle.

Another object of the present invention is to provide an ash receptacle having an ornamental front adapted to serve as a means by which the ash receptacle may be drawn out into its open position.

Other objects and features of this invention will more fully appear from the following detailed description taken in connection with the accompanying drawing, which illustrate two of the preferred embodiments thereof, and in which:

Figure 1 is a face view of one of the preferred embodiments of my novel container or ash receptacle structure;

Figure 2 is a plan view of the ash receptacle structure shown in Figure 1, a portion thereof being broken away to more clearly show the construction;

Figure 3 is a cross section taken on the line 55 of a cross section taken on the line 55

III—III of Figure 1 and looking in the direction of the arrows;

Figure 4 is a section on the line IV—IV of Figure 2, looking in the direction of the arrows, and is on an enlarged scale; and

Figure 5 is a portion of a section similar to the left part of Figure 3 and showing a modified form of the invention.

As shown on the drawing:

- 10 One of the preferred forms of the invention is designed to be mounted upon the rearwardly projecting flange 11 of an instrument panel 10, and comprises two principal parts, a retainer 12 which is fixed to the instrument panel flange 11 by suitable bolts 13 and a drawer-like ash receptacle 14 which is slidably supported by the retainer 12 and can be drawn out to its open position, shown in dotted lines in Figure 3, from under the instrument panel 10.
- 20 The retainer 12 is formed of a single rectangular piece of sheet metal bent and stamped into the desired shape. The retainer 12 is formed with a pair of flat, longitudinally extending ribs 15 which form reinforcements through which are punched the holes 16 for the bolts 13 which fix the retainer in position. Along the center of the retainer 12, there is provided a pair of small narrow ribs 17 which project below the surface of the main portion of the retainer and form tracks which are pressed upon from underneath by a spring 18 carried by the drawer 14 and described in detail below. Near the front edge of the retainer 12, a small downwardly projecting stop 19 is stamped out of the metal 35 between the two ribs 17 and is adapted to engage a portion of the spring 18 on the drawer 14, as will be explained in greater detail below.

The two lateral edges of the retainer 12 are bent down to form depending flanges 21 at 40 the sides of the retainer and are then bent diagonally in to form longitudinally extending, laterally sloping tracks 22 upon which the ash retainer 14 is supported.

The body or main portion 23 of the ash retainer 14 may be formed from several pieces of sheet metal spot welded together, or may be drawn in a single piece, the latter construction being the one shown in the drawing. The general shape of the ash receptacle body 23 is that 50 of an open topped box or drawer. Near the top, the two lateral sides of the ash receptacle body 23 flare out at an oblique angle to form slide portions 24 adapted to rest upon the track portion 22 of the retainer and to thus slidably support the ash receptacle. The sides of the ash

receptacle body 23 extend up vertically a fraction of an inch above the slide portions 24 and are then bent in to form horizontal strengthening flanges 25 extending from front to back of the ash receptacle body.

The front of the ash receptacle body 23 is covered by a decorative and ornamental face plate 26 which may be formed of a plastic or any other suitable material. In the form of the invention shown in Figures 1 to 4, the face plate 26 is formed with a transversely extending projection 27, which serves as a handle, and its lower part curves around under the front of the ash receptacle body 23, as shown in Figure 3. In order to enhance its appearance, the front of the face plate 26 is formed with a vertical rib 28 below each end of the handle 27, and the handle 27 is formed with a central vertical slot 29 dividing it into two portions. The face plate is secured in place by a pair of screws 31 which extend through the front of the ash receptacle body 23 and into the handle portion 27 of the face plate, and by a single centrally located screw 32 which extends up through the portion of the face plate extending around under the front of the ash receptacle body and through the bottom of the ash receptacle body. The screw 32, extending up through the rearward extension of the face member 26, is placed far enough back so that it cannot be seen by a person seated in the normal position facing the ash receptacle, and the screws 31, extending into the handle portion 27, fit into blind holes. Thus, the entire means for securing the face member 26 are normally concealed.

The spring 18, which bears against the two small ribs 17 on the bottom of the retainer 12, extends longitudinally of the ash receptacle 14 and is carried by the front and rear walls thereof. The front end 33 of the spring 18 fits into a notch in the front wall of the ash receptacle body 23 and extends down a short distance between the front of the ash receptacle body and the back of the face plate 26, terminating in a short lip 34 which extends forward into a slot in the back of the face plate 26. This holds the front end of the spring 18 in place and prevents the entire spring from sliding forward or backward. The rear end of the spring 18 passes over a lug 37 stamped out of the container body 23 and through an aperture 38 which is formed in part by the stamping out of the lug 37.

The forward portion of the spring 18 is shaped and punched out to form a shallow cup 39 having a pair of cross bars 41 extending across its otherwise open bottom. The cup 39 serves as a snuffer into which the lighted end of a cigarette can be inserted and twisted around, the cross bars 41 acting to remove the lighted portion of the tobacco and to thus extinguish the cigarette.

The central portion of the spring 18 is formed into a hump 42 which presses up against the underside of the small ribs 17 on the retainer 12. The sloping forward side of the hump 42 is provided with an aperture 43 which is in line with the stop 19 at the front of the retainer 12 and which extends up the front of the hump 42 to the horizontal top portion 44 of the hump. This permits the front edge of the horizontal top 44 of the hump to engage the stop 19 on the retainer when the ash receptacle 14 is drawn forward to the position shown in dotted lines in Figure 3 and makes the stop 19 effective instead of allowing it to ride over the sloping front surface of the hump 42. At either side of the

hump 42, the spring 18, which is weakened at this point by the hole 43, is strengthened by a narrow depending flange 45.

The rear end of the spring 18, which projects 5 through the aperture 38 in the back wall of the ash receptacle 23, extends out a short distance and then curves up and back upon itself and passes forward over the back of the ash receptacle body 23. The extreme end of the spring 10 18 is curved and slotted longitudinally to provide two laterally spaced rounded portions 46 which bear up against the small ribs 17 on the bottom of the retainer 12.

It will be noted that the spring 18, which 15 forms a part of the ash receptacle 14, presses up against each of the small ribs 17 at two longitudinally spaced points, one at the central hump 42 and the other at the end 46. The pressure thus applied prevents the ash receptacle 14 from 20 rocking or tipping fore and aft even when it is withdrawn to its open position and only a short length of each of the slide portions 24 is in contact with the tracks 22 on the retainer. It may also be noted that, when the ash receptacle 14 25 is withdrawn to its open position and the top 44 of the hump is engaged with the stop 19 on the retainer, the central portion of the spring may be flexed downwardly by applying pressure to it immediately in front of the hump 42, and that the spring may thereby be disengaged from 30 the stop 19. This permits the ash receptacle 14 to be withdrawn completely from the retainer 12 and the contents of the receptacle emptied. It will be noted that the end portions 46 at the 35 end of the spring are separated by a slot and that, when the ash receptacle is being withdrawn completely from the retainer, these end portions 46 will pass at each side of the stop 19 and present no obstacle to the complete withdrawal of the 40 ash receptacle.

The modified form of ash receptacle 51 and retainer 52 are similar in most respects to the form shown in Figures 1 to 4. The chief difference is that the lower portion 53 of the front 45 of the ash receptacle body 54 slopes back away from the lower portion of the face member 55, which is secured to the upper portion 57 of the front of the ash receptacle body by a pair of screws 56. Thus, a nook 58 is provided behind 50 the lower part of the face member 55 into which the fingers can be hooked in order to withdraw the ash receptacle 51. This makes it unnecessary to provide a projecting handle portion, and permits the ash receptacle to fit into a design of 55 instrument panel assembly in which such a projecting handle portion might be objectionable. In the particular design shown in Figure 5, the instrument panel 59 is provided with portions 61 which extend down at each side of the ash receptacle 51, so that the face member 55 and the surrounding portions of the instrument panel 59 60 present a substantially smooth and level surface.

It will, of course, be understood that various 65 details of construction may be varied through a wide range without departing from the principles of this invention and it is, therefore, not the purpose to limit the patent granted hereon otherwise than necessitated by the scope of the appended claims.

70 I claim as my invention:

1. In an ash receptacle having a front wall member covered by a face member and having a rear wall member, a retainer engaging spring having the rear end thereof extending through an aperture in said rear wall member and having

the front end thereof extending over the top out of said front wall member and down between said front wall member and said face member, the extreme end of said downwardly projecting portion of said front end of said spring being formed to provide a horizontally extending lip engaging a shoulder on one of said members for preventing upward movement of said front end of said spring.

2. In an ash receptacle structure a retainer, 10 an ash receptacle, cooperating means on said retainer and receptacle for guiding said receptacle in movements between open and closed positions,

and a spring having the front end thereof fixedly attached to and supported by the front of said receptacle and the rear end thereof restrainingly cooperating with the back of said receptacle, said spring having an intermediate portion thereof in frictional engagement with said retainer and having said rear end thereof overhanging and resting on an edge of the back of the receptacle and reversely curved upwardly and back towards the front of said receptacle and in resilient engagement with said retainer.

JOHN VISSER.
